CONTAINER AND METHOD OF MAKING
SAME

Frank Gilbert, Jr., Olmsted Falls, Ohio

Application May 4, 1942, Serial No. 441,649

8 Claims. (Cl. 93—36)

1

This invention relates to an improvement in containers and methods of making said containers. More particularly, this invention relates to a method of rendering containers of fibrous sheet material exceptionally rigid, liquid-proof and impervious to most common gases and vapors.

Heretofore, containers of fibrous materials, such as paperboard, chipboard, strawboard, or like paper stocks, generally have not been satisfactory for packaging heavy materials or materials which are likely to lose or absorb moisture. In the first place, such containers seldom possessed sufficient rigidity unless the wall thicknesses were increased to unwieldy proportions. In the second place, such containers, unless they were lined with comparatively expensive impervious liners, were not impervious to gases and vapors, such as air and moisture vapor. Consequently, the general practise has been to employ more expensive metal or glass containers when the substance to be packaged required a rigid and impervious container, particularly when it was desirable to maintain a vacuum within the sealed container.

It is an object of this invention to provide an inexpensive container of fibrous material which will be substantially impervious to common liquids, gases, and vapors and which will possess a rigidity and strength approaching that of the well-known metal and glass containers.

Another object of this invention is to provide a fibrous container and a method of sealing which will permit a vacuum to be created and maintained within the container.

It is also an object of this invention to provide a double-wall container having a hermetically sealed space between the walls of the container.

Other and further objects and advantages of this invention will be apparent from the following specification, claims, and drawing, in which:

Fig. 1 is a cross-section of an outer shell and an elevation of an inner shell showing a manner of assembling a container made according to my invention.

Fig. 2 is a cross-section taken along the line 2—2 of Fig. 1 showing one form of an assembled container made according to my invention.

Fig. 3 is a view similar to Fig. 2 showing another form of an assembled container made according to my invention.

In the drawing, in which like reference characters refer to like parts, 10 represents an outer shell or container comprised of a spirally wound tube 11 having one end spun in to provide an inner flange 12 on which a disk 13 is seated to 55

2

provide a bottom closure for the tube 11. The tube 11 is closed with a top cap 14 similar in construction to the bottom closure of the tube 11. 20 represents an inner shell or container comprised of a spirally wound tube 21 closed at one end with a bottom closure cap 23 of stamped paper and at the other end with a top closure cap 24 of stamped paper. The bottom cap 23 is provided with a suitable spacer 25 and the tube 21 is likewise provided with suitable centering spacers 26. The outer shell 10 and the inner shell 20 are both preferably comprised entirely of fibrous sheet material, such as heavy kraft paper, chipboard, paperboard, strawboard, or like paper stock. The outer surfaces of the outer shell 10 may be suitably glazed or lacquered and may carry any desired printing or label. The inner surface of the tube 21 and cap 23 may also be suitably glazed or coated, if desired. As will be apparent from the following, it is preferable that the inner surface of the outer shell 10 and the outer surface of the inner shell 20 should be unglazed or, at the most, only slightly glazed or finished in order to allow the shells to be impregnated with the filler. Also, it is preferable that the top cap 24 be made of porous stock carrying only a small amount, if any, of sizing or filler which tends to render the stock non-porous. The closures for the outer shell 10 are shown as being of the well-known spun tube and disk construction and the closures for the inner shell 20 are shown to be stamped paper caps, in order to illustrate two types of closures, each of which may be used for both shells. Obviously, other types of end-closures may be used for the shells where such other types of closures would be convenient and practical.

The several spacers 25 and 26 are preferably embossed or deeply scored projections on the inner shell 20. Such spacers, however, may also be made by attaching strips or spots of paper stock, or non-porous material, such as sealing wax, to the outer surfaces of the inner shell 20. It is also apparent that the same function of centering and spacing the inner shell 20 in the outer shell 10 would be served by similar spacers on the inner surface of the outer shell 10.

A preferred manner of assembling my container is shown in Fig. 1. The open outer shell 10 is partly filled with a molten filler 30 which is substantially solid at normal atmospheric temperatures. The closed inner shell 20, filled with the substance to be packaged, 40, is then inserted in the outer shell 10 while the filler 30 is still in a fluid condition. As the inner shell 20 is placed

within the outer shell so that it is centered in the outer shell by the spacers 26 and spaced from the bottom 13 by the spacer 25, the molten filler is extruded up between the walls of the inner and outer shells, completely filling the space therebetween up to the level attained due to its displacement by the shell 20. The filler 30 is then allowed to solidify. The cap 14 may be placed on the open end of the shell 10 either after or before the filler solidifies, depending upon whether a completely filled container, as shown in Fig. 2, or a hollow wall container, as shown in Fig. 3, is desired.

The filler 30 is preferably a wax, such as paraffin, and/or a resin, such as pine rosin, which will not only solidify into a rigid mass at atmospheric temperature but which will also penetrate and impregnate the walls of the inner and outer shells. A mixture of paraffin wax and rosin is often preferable for the filler 30, since the mixture of the two cheap constituents of such a filler is less brittle than either of the constituents alone. It is obvious, however, that one may use any other suitable and normally solid filler, plasticized if necessary, which is substantially impervious to the gases, vapors, or liquid which it is desired either to retain in the packaged contents 40 or from which the packaged contents are to be protected. A mixture of paraffin wax and pine rosin is usually a satisfactory filler when it is desired to have the package impervious to air, water and water-vapor, and many petroleum products. How my container prevents leakage of petroleum products which normally seep or wick through vessels consisting only of paper stock or only of the filler is not understood.

By employing a top cap 24 which is of porous stock, I achieve a vacuum packaging of the contents 40. When the closed inner shell 20 is inserted into the outer shell 10 partly filled with the hot molten filler 30, the contents 40 are heated and expanded, expelling air and other gases within the shell 20 through the porosities of the inner shell 20, and, particularly, through the porosities of the cap 24. As the filler 30, which surrounds the inner shell 20, cools and solidifies, however, the porosities in the shell 20 are filled and impregnated by the solidifying filler. Consequently, air does not return into the inner shell as the contents of the inner shell (including residual gases, if any) cool and tend to contract. Thus, the inner shell is thoroughly sealed and at least a partial vacuum is created and maintained within the inner shell.

It is often preferable and advantageous to have the inner shell 20 and contents 40 heated when the inner shell is immersed in the molten filler 30. The advantages generally obtained are: first, freezing or solidification of the filler is delayed, thereby preventing the formation of voids which extend across the space between the shells and cause portions of the walls of the shells to be uncoated or unimpregnated by the filler; second, impregnation of the inner surface of the outer shell and of the outer surface of the inner shell is assisted; third, the vacuum within the inner shell tends to be increased.

In the container illustrated in Fig. 2, the filler 30 completely fills the space between the inner and outer shells. This construction is obtained by placing in the open shell 10 a volume of molten filler approximately equal to the total volume of space between the shells and the volume of filler impregnated in the shells. If the inner shell tends to float in the molten filler, pressure should be

applied to maintain the spacer 25 in contact with the bottom 13 until the filler solidifies sufficiently to prevent the inner shell from floating. If the filler tends to shrink when cooling, a sufficient amount of filler should then be added to fill the outer shell before closing it with the cap 14.

The container illustrated in Fig. 3 is provided with a substantially hollow wall. This construction is obtained by placing a slightly lesser amount of filler in the open outer shell 10, inserting the closed inner shell 20, closing the outer shell with the cap 14 and then, while the filler is still molten, inverting the package so that filler will flow into the space between the cap 14 and the inner shell 20. To prevent the inner shell 20 from falling into said space, it is preferable to provide the cap 24 with a spacer 27, as shown in Fig. 3. To prevent the filler from freezing or solidifying as the package is inverted, so that flow of the filler into the space between the caps 24 and 14 would be prevented, it is particularly desirable that the contents of the shell 20 be heated. By repeated inversions of the package as the filler cools, a hollow wall container, in which both the inner surface of the outer shell 10 and the outer surface of the inner shell 20 are impregnated and hermetically sealed, will be obtained. In most instances, fins or flutes of filler will extend between the shells, thereby strengthening the walls of the package.

From the foregoing, it should be apparent that containers made according to this invention may be modified as to the shape and structure of the inner and outer shells, the closures therefor, and the composition of the filler as the requirements of specific packages will dictate to those skilled in the art. It is to be understood, therefore, that this invention is not to be considered to be limited to the specific embodiments disclosed, either in whole or in part, but by the following claims.

What is claimed is:

1. A method of rendering a container of fibrous material substantially impervious and of increasing the rigidity of said container comprising the steps of placing in an outer shell of fibrous stock a quantity of liquid filler which is normally substantially solid, inserting an inner shell of fibrous stock in said outer shell while said filler is liquid to extrude said filler between the walls of said shells, and then allowing said filler to solidify.

2. A method of rendering a container of fibrous material substantially impervious and of increasing the rigidity of said container comprising the steps of partly filling an open outer shell of fibrous stock with a molten filler which is normally substantially solid at atmospheric temperatures, inserting a closed inner shell of fibrous stock in said outer shell while said filler is molten to extrude said filler between the walls of said shells and to impregnate the inner surface of said outer shell and the outer surface of said inner shell at least partly with said filler, and maintaining said inner shell within and spaced from said outer shell while said filler is allowed to cool and solidify.

3. The method of sealing and creating a vacuum within a container of fibrous stock comprising the steps of filling a quantity of molten filler, which is normally solid and substantially impermeable to gases, in an open outer shell, placing a closed inner shell, of which at least a portion is comprised of porous fibrous stock, within said outer shell, the quantity of filler in said outer shell being sufficient to permit said inner shell to be submerged in said filler and the fibrous

stock of said inner shell being sufficiently porous to permit gases enclosed in said inner shell to escape through said fibrous stock, and then allowing said filler to solidify while said inner shell is submerged.

4. The method of sealing and creating a vacuum within a container of fibrous stock as defined in claim 3 including the steps of heating the contents of said inner shell to a temperature above normal atmospheric temperatures prior to inserting said inner shell in said outer shell, and inserting said inner shell in said outer shell while said contents are heated.

5. The method of making a container of fibrous stock substantially impervious to liquids and gases comprising the step of partly filling an open outer shell of fibrous stock with a quantity of molten filler and impregnating agent which is normally substantially solid and impervious to the liquids and gases to which it is desired to render the container impervious, inserting a closed inner shell of fibrous stock in the outer shell while said filler and impregnating agent is still molten to extrude said filler and impregnating agent between the walls of said shell, allowing said filler and impregnating agent to cool and solidify, pouring an additional quantity of filler and impregnating agent in said outer shell to fill said outer shell completely with said filler and impregnating agent, and then closing said outer shell.

6. The method of making a container of fibrous stock substantially impervious to liquids and gases as defined in claim 5 including the steps of

heating the contents of said inner shell prior to inserting said inner shell in said outer shell, and maintaining said inner shell submerged in said filler and impregnating agent and spaced from said outer shell while said filler and impregnating agent is allowed to cool and solidify.

7. The method of making a double wall container of fibrous stock which is impervious to liquids and gases comprising the steps of partly filling an open outer shell of fibrous stock with a molten filler and impregnating agent which is normally solid at atmospheric temperatures, inserting a closed inner shell of fibrous stock in said outer shell while said filler and impregnating agent is molten to extrude said filler and impregnating agent between the walls of said shells and to impregnate, at least partly, a portion of the surfaces of the walls of said shells, closing said outer shell, and then inverting said shells while said filler and impregnating agent is still molten but while said shells are cooling to impregnate, at least partly, the remainder of the inner surface of the walls of said outer shell and the outer surface of the walls of said inner shell.

8. The method of making a double wall container of fibrous stock as defined in claim 7 including the steps of heating the contents of said inner shell prior to inserting said inner shell in said outer shell, and maintaining said inner shell spaced from said outer shell while said filler and impregnating agent is solidifying and impregnating the walls of said shells.
